Associates, Inc., Wilkes-Barre, Pa., a corporation of Pennsylvania

Filed June 10, 1964, Ser. No. 80,348

Term of patent 14 years

(Cl. D33—14)

The dominant features of my design reside in those portions shown in full lines in the drawings.

I claim:

The ornamental design for an end table, substantially as shown and described.
